MOBILE HOME

Leo F. Dufrechou, 4033 Veterans Blvd.,
Metairie, La. 70005

Filed May 29, 1973, Ser. No. 364,549

Term of patent 14 years

Int. Cl. D12—10

U.S. Cl. D12—103

FIG. 1.

FIG. 6.

FIG. 1 is a left front perspective view of a Mobile Home showing my new designs;

FIG. 2 is a left side elevational view thereof;

FIG. 3 is a right side elevational view thereof;

FIG. 4 is a front elevational view thereof;

FIG. 5 is a rear elevational view thereof; and

FIG. 6 is a top plan view thereof.

The broken lines in the drawing are for illustrative purposes only.

I claim:

The ornamental design for the mobile home, as shown and described.
